UNITED STATES PATENT OFFICE.

EZRA P. WATERHOUSE AND CARL HENRY LEKBERG, OF WORCESTER, MASSACHUSETTS.

ENVELOPE MACHINE.

Application filed January 20, 1923. Serial No. 613,846.

To all whom it may concern:

Be it known that we, EZRA P. WATERHOUSE and CARL HENRY LEKBERG, citizens of the United States, residing at Worcester, in the county of Worcester and State of Massachusetts, have invented certain new and useful Improvements in Envelope Machines, of which the following is a specification.

10 Our present invention relates to a novel construction and organization of means for operating the gum-distributing element or devices whereby gum or adhesive is spread upon the faces of the pickers, in an envelope machine of the picker-plunger class; a prime object of this invention being to provide a mechanism that will be satisfactory and efficient for action; better adapted for operation at high speed; and to obviate some objections incident to mechanisms heretofore employed in this art.

15 Another object is to provide in the gumming mechanism of an envelope-machine, a flexible cord or cable connection for the reciprocation of the gum transfer-roll by alternately directed pulling action; thus affording a light-running, quiet, and slightly elastic mechanism.

20 Another object is to provide a gumming mechanism, in an envelope-machine of the class named, with a flexible cord, band or cable and cable-guiding means, arranged for reciprocatively moving the gum-transferring element from the gum-supply across the pickers, and vice versa, and oscillating drum or element for actuating said cable alternately in opposite directions, and means for imparting movement to said oscillating element synchronous with the action of the envelope-machine mechanism.

25 A further object is to provide in combination with the reciprocatingly moving gum-transferring roll, its guides, and operating cable; of means for attaching the cable to the roll-supporting carriers or slides in a manner to afford adjustability, security of connection, and elasticity of action.

30 These objects we attain by mechanism the nature and organization of which is explained in the following detailed description; reference being therein made to the accompanying drawings (three sheets) wherein—

35 Fig. 1 represents an elevation view of

such parts of an envelope machine as will 55 illustrate the nature of our invention,

Fig. 2 is a front view,

Fig. 3 a plan view above the stripper-plate, the picker-plunger being in section.

Fig. 4 is a detail side view on larger scale 60 of the roll-carrier slide and section of the cable attaching means.

Fig. 5 a section of the cable attaching means at line X—X on Fig. 4.

Fig. 6 a disk-wise view of the cable-winding drum, and

Fig. 7 a part side part section view of the cable-winding drum.

Referring to the drawings, the letter A indicates the frame of an envelope-machine; 70 B the table; C the drive-shaft; D the picker-plunger, carrying the pickers and whereby the gum or adhesive substance is placed upon the envelope blanks; and E the blank-supporting elevator or stand; all 75 of which parts may be of well known or any suitable construction; as may also the mechanisms required for transferring and folding the envelope blanks, which mechanisms are not herein shown, since they form 80 no essential part of our present invention; but it will be apparent that, in practice, our improvement is designed to be employed in connection with a machine of the character 85 named; the operation will, therefore, be sufficiently understood by persons skilled in the art.

The numeral 10 indicates the stripper-plate arranged above the stand of blank F, and having openings therein through which 90 the pickers descend to contact with the blank in well known manner. 12 denotes the gum-box having the gum-delivering roll 13 rotatably mounted therein and provided with means for its operation, and means for regulating the film of gum delivered thereby. 15 indicates the transfer-roll, its axle journaled in or supported by suitable carriers or slide members 16 mounted to move on guides or rods 14 disposed horizontally 100 above the stripper-plate 10, parallel with each other; said members 16 are arranged to travel along the guides 14 for a distance sufficient to carry the roll 15 into contact with the gum delivery-roll 13, and back to the position indicated in full lines on Fig. 2, said transfer-roll passing across the faces 105 of the pickers 2 when elevated, for charging

said pickers with gum; also performing a dwell at or adjacent the position indicated, while the pickers descend through the stripper-plate for picking up a blank and 5 are again elevated.

The employment of a reciprocally moving transfer-roll traveling from contact with the gum supply across the faces of the pickers for placing gum thereon being well-known 10 in the art, it will be apparent that we do not claim such feature, per se, as of our invention.

In accordance with our invention, for imparting reciprocatory back and forth movement 15 to the transfer-roll 15, we employ a flexible beltlike connection consisting of a suitable cord or cable of wire 5; an oscillating element or drum 6 by which said cable is operated, and means for actuating said 20 drum synchronous with the elevated dwell of the picker-plunger and envelope-machine action. The cable 5 is best formed about three sixteenths inch, more or less, in diameter, and may be made of any suitable material; it is preferably composed of a group 25 of small flexible wires twisted together. This cable is arranged about a series of guide pulleys or sheaves that are rotatably supported in adjacent relation to the path 30 of the transfer-roll 15. Most of the sheaves are mounted in overhead horizontal relation upon studs that have their support in brackets 9 attached to an upper frame number A¹ of the machine; thus leaving unobstructed space beneath the cable and sheaves. 35 The cable is arranged in such manner that two portions or reaches thereof, as 5^a and 5^b, will simultaneously travel in the same direction and said two portions are attached 40 respectively to the front and rear carriers 16 in which the axles of the transfer-roll are supported.

At a convenient position, the cable 5 is connected with an oscillating element or 45 means for effecting longitudinal pulling action one way and the other, said element preferably consists of a drum 6, upon the periphery of which the cable is wound from opposite sides, and to which the cable is secured 50 at a predetermined position by a suitable stay or clamp 8. The surface of the drum is preferably spirally grooved for guiding the coils of cable thereon.

The drum 6 may be located at any convenient position in relation to the roll-carrier means and the cable extended thereto, direct or about guide sheaves, as may be most convenient to accommodate the machine structure in any instance. As shown 60 the drum 6 is mounted in connection with a gear pinion 17, upon an axis stud 18 supported in a stationary bracket 19 near the lower part of the frame. (See Figs. 1 and 2.) A reciprocating bar or member 20 car-

ries a rack 21 that engages with the pinion 65 17. Said rack-bar is arranged to be actuated by a rotating cam 23 mounted on the the drive-shaft C, or some conveniently disposed shaft in the machine, whereby the cam is revolved in unison with the stroke of the 70 envelope forming devices. The bar 20 is provided with a stud or roll 22 that engages with the grooves of the cam 23, and said bar is preferably centrally furcated for guiding 75 upon the cam-shaft; its upper and lower portions being supported to work in proper relation by guiding means fixed on the frame or table in any approved manner. A pull spring 24 is preferably connected with the rack-bar to normally keep the roll-stud 80 against the cam surface. The cam 23 is made of suitable form and dimension for imparting through the rack and pinion, to the oscillating element or drum 6 the requisite degree of oscillative movement for pulling 85 the cable alternately right and left and thereby moving the roll-carrier slides 16 and roll 15 back and forth along the guides 14, the operation being a pull action in each direction. 90

As illustrated the cable 5 extends from the drum 6 up to a plane slightly above the plane of the guides 14, and over a guiding sheave 26, thence horizontally toward the right and around a sheave 27 and rearward about a sheave 28; thence towards the left in rear of the picker mechanism 2 and around a sheave 29; thence towards the right to a sheave 30 below the sheave 28, then forward and about a sheave 31 above the sheave 27; thence to the left across the front and to a sheave 32 adjacent to the first mentioned sheave 26 and down to the drum 6 which it meets at the side opposite that from which it starts. The cable, which is preferably continuous, is secured to the periphery of the drum, by the fastener 8, so that as the drum is oscillated the cable will be wound onto said drum at one side while it is equally unwound from the other side, and vice versa; hence the cable is alternately pulled lengthwise in one direction and the other in unison with the oscillative movement, without material variation in the general tension of the cable. Guide sheaves 33 and 34 are provided where the cable deviates from a direct line between the drum and upper mechanism. At one or more positions in its length the cable 5 may be provided with a turnbuckle 25 or means for 100 taking up slack or adjusting its tension. 110

The two reaches of cable 5 respectively disposed at front and rear approximately parallel with the guides 14, and arranged to simultaneously move in the same direction, 115 and indicated by numerals 5^a and 5^b, are attached to the respective slides or carrier members 16 of the transfer-roll 15, so that 120 125

said members together with the roll 15 are moved with the movement of the cable; the two carriers or roll bearing members moving approximately in unison and to the same extent. The attaching means is best constructed as shown in Figs. 4 and 5. The roll-supporting slide 16 is mounted with two lugs 3 and 3^x upon the guide 14, the lugs being some space apart. Between said lugs, also mounted on the guide, there is a coupling-block 35 having jaws projecting into line with the cable and provided with a clamping member or cap 36 secured by suitable means, as a screw, or screws S. The inner faces of the jaws are best fitted with a recess on one part and protuberance on the other part opposite said recess. The cable extends through said jaws and the cap is firmly clamped down causing a slight bend or offset 4 in the cable (see Fig. 4) which prevents slipping of the cable therein.

Coiled wire springs 7 are preferably arranged, at one or both sides, between the coupling-block and lug on the roll-supporting member, to prevent shock and for easing the action at the reversal of the direction of motion of the reciprocatively moving parts. Said springs may not in all instances be required and can in some instances be omitted if so preferred.

This mode of attachment permits ready adjustment of the cable in relation to the roll: gives security of connection, and affords a slight degree of elasticity in action.

We claim as our invention and desire to secure by Letters Patent—

1. The combination with gumming mechanism in an envelope machine, including a reciprocally acting transfer-roll, and roll-carrier means; of a flexible cable-form carrier-operating element, means for supporting and guiding said element, and means for imparting back and forth movement thereto, for the purpose set forth.

2. In a device for the purpose described a reciprocally moving transfer-roll, a flexible cable connected with and arranged for moving said transfer-roll, and means actuated in conjunction with the envelope-producing mechanism for alternately pulling said cable in opposite directions.

3. An envelope gumming mechanism including a reciprocating gum-transferring element, a flexible cable means connected for reciprocally moving said gum-transferring element from the gum-supply across the pickers, and vice versa, an oscillative element actuating said cable means longitudinally in alternate directions, and means for imparting movement to said oscillative

element synchronous with the action of the envelope-machine mechanism.

4. In an envelope-machine, in combination with the plunger pickers, gum supply means, gum transfer-roll, and guides for said transfer-roll; of a roll operating means comprising a flexible connection cable, a series of guide sheaves about which said cable is arranged to present two reaches that simultaneously move in the same general direction, means attaching said reaches of cable to the respective carrier members for the ends of said transfer-roll, and means for effecting alternate longitudinal back and forth pulls on said cable.

5. In an envelope-machine of the class described, comprising a gum-supply, vertically moving blank-gumming pickers and a laterally moving gum-transfer-roll traveling from the gum-supply across the faces of the pickers; the combination with the transfer-roll carriers, of a cable connected therewith for moving said roll, a series of guiding sheaves supporting and directing said cable, an oscillating drum to which said cable is connected for winding onto and from the periphery at opposite sides, a pinion operatively connected with said drum, a reciprocating member carrying a rack engaging said pinion, and a revolving cam working with the envelope-machine mechanism and adapted for actuating said rack-carrying member.

6. In combination with the reciprocating gum-transferring roll, parallel guides therefor, roll-supporting carriers slidable on said guides, a flexible cable controlling the carriers, and means for operating said cable; of means for the attachment of said cable to the carrier comprising a laterally projecting member united with the carrier and having a cable receiving space within which the cable is clamped.

7. In an envelope-machine, in combination with the reciprocating picker-gumming roll, parallel guides therefor, roll-supporting carriers slidable on said guides, a pulling-cable connection and means for operating the same; of means for uniting the cable and roll-supporting carrier, comprising a coupling-block mounted between lugs formed on the carrier and slidable on the guide, an expanding spring arranged between the coupling-block and lug, said coupling-block provided with cable-receiving jaws internally fitted with coacting offset grip-faces, and means for clamping said jaws rigidly upon the cable laid between said grip-faces.

EZRA P. WATERHOUSE,
CARL HENRY LEKBERG.
